UNITED STATES PATENT OFFICE.

LAZARD KAHN, OF HAMILTON, OHIO, ASSIGNOR TO F. & L. KAHN & BROS.,
OF SAME PLACE.

DESIGN FOR AN ASH-BOX FOR STOVES.

SPECIFICATION forming part of Design No. 25,133, dated February 4, 1896.

Application filed December 23, 1895. Serial No. 573,162. Term of patent 14 years.

To all whom it may concern:

Be it known that I, LAZARD KAHN, a citizen of the United States, residing at Hamilton, Butler county, Ohio, have invented and produced a new and original Design for Stove Ash-Boxes, of which the following is a specification, reference being had to the accompanying drawing, which is a perspective view showing my design.

The leading feature of my design consists in an ash-box from the upper surface of which upwardly projects one or more circular registers having upwardly-projecting handles at their centers.

A indicates the ash-box. B indicates the 15 circular registers projecting upwardly from the upper surface thereof.

C indicates the handles projecting upwardly from the centers of the registers B.

What I claim is—

The design for a stove ash-box, as shown and described.
